MACHINE FOR OPERATING UPON THE END PORTIONS OF SHOES

Filed May 15, 1935

UNITED STATES PATENT OFFICE

2,036,086

MACHINE FOR OPERATING UPON THE END PORTIONS OF SHOES

Francis J. Better, Beverly, Mass., assignor to
United Shoe Machinery Corporation, Paterson,
N. J., a corporation of New Jersey

Application May 15, 1935, Serial No. 21,631

19 Claims. (Cl. 12—14)

This invention relates to machines for working the end portions of shoe upper over their lasts and, as illustrated herein, is embodied in a machine for working the foreparts of stitchdown shoe uppers into lasted position and for pressing the outturned flanges thereof against the projecting margins of the soles.

Objects of the invention are to improve and perfect machines of this type such, for example, as that disclosed in Letters Patent of the United States No. 1,955,730, granted April 24, 1934, in the name of William C. Baxter. More specifically, objects of the invention are to apply pressure to the upper to hold it against the last before the lasting operation begins, to maintain said pressure while the machine is at rest with the outturned flange of the shoe upper and the projecting margin of its sole under pressure, and to relieve said pressure just prior to the relief of the pressure upon the flange and sole.

Further objects of the invention are to adapt the machine for lasting uppers over lasts the sides of which are undercut.

In the illustrative machine, as in prior machines, the shoe, including the projecting margin of the sole, rests on the shoe support and lasting means, such as end-embracing wipers which have advancing and closing movement, are provided, the shoe support and wipers being relatively movable heightwise of the shoe to effect the shaping of the upper to the contour of the last and the pressing of the outturned flange thereof against the projecting margin of the sole, the wipers being positively advanced after the relative heightwise movement between the wipers and shoe support has ceased to work the fold of the upper in the angle between the side of the last and the projecting margin of the sole slightly under the last bottom, the shoe being allowed to remain in this condition for a time, for instance while another shoe is being lasted, in order that the upper may become set in lasted position.

In accordance with the present invention, means is provided for clamping the upper against the last prior to the relative movement of the wipers and the shoe support so that the upper cannot become bridged from the toe to the throat of the vamp, due to the tension applied to the upper during the lasting operation, and said pressure is maintained substantially throughout the period during which the wipers and shoe support remain in pressing relation to the outturned flange of the upper and the projecting margin

of the sole, means being provided, for example a treadle by which the machine is restarted, for relieving the pressure from the toe of the shoe just prior to the relief of pressure upon the flange and sole.

Another feature of the invention consists in means which may be rendered operative at will for effecting advancing and closing movements of the wipers earlier in the cycle of the machine, that is, during the relative heightwise movement between the wipers and the shoe support, the amount of such earlier movement being variable to include any part of or the full movement of the wipers. The organization is such that the portion of the wiper movements which do not occur earlier in the cycle occur later and at the usual time, that is, after the relative movement between the wipers and the shoe support is substantially completed. This construction adapts the machine for use under conditions of work where the sides of the last overhang the bottom portion of the last, that is, where the sides of the last are undercut adjacent to the last bottom. By causing a portion of the wiper movement, depending upon the amount of undercut of the last, to occur earlier in the cycle, that is, while there is a substantial space between the wipers and the outwardly projecting margin of the sole, the wipers are made to conform the upper to the undercut portion of the sides of the last and to be located above fastenings, such as staples, which may have been previously applied to hold the upper shaped to the last at certain portions of the toe, so that when the final movement of the wipers occurs the wipers will slide over the top of the staples and not disturb or injure them.

Preferably and as illustrated herein, the relative heightwise movement between the shoe support and the wipers is caused to cease during those portions of the cycle when the advancing and closing movements of the wipers are occurring.

These and other features of the invention will appear more fully from the following detailed description when read in connection with the accompanying drawing and will be pointed out in the appended claims.

The figure of the drawing is a side elevation, partly in section, of a machine embodying the present invention.

In general organization the machine is similar to that disclosed in the above-mentioned patent and hence its construction will be described rather generally since reference may be had to

said patent for explanation of structural details not herein fully set forth.

A frame 10 carries bearings for a main shaft 12 upon which is mounted a clutch disk 14 having a cam track 16 in one face thereof. A stop projection 20 on the clutch disk 14 is arranged to engage a stop arm 22 which is pivotally mounted on a shaft 24 supported on the frame of the machine and has a forwardly projecting arm 10 which carries a tripping pin 26. The pin 26 is slabbed off at its front side and cooperates with a vertical bar 28 having an elongated notch 30 which engages the tripping pin. The bar 28 is connected to a treadle 32 and when the treadle 15 is depressed the upper end of the notch 30 will, after a certain amount of lost motion, engage the pin 26 and, by lifting the stop arm 22 from engagement with the projection 20, will permit the clutch to engage and the machine to start. After 20 the machine starts, the bar 28 is pushed forwardly by a projection on the periphery of the clutch disk 14 to free the notch 30 from the pin 26, thus allowing the stop arm 22 to drop back into position and, after a half revolution 25 of the clutch disk 14, to engage a projection 34 opposite to the projection 20, thereby stopping the machine with the outwardly projecting margins of the upper and sole under pressure between the wipers and the shoe support, as will be described. The clutch operates to connect the clutch disk 14 to a gear 36 and to disconnect it therefrom, the gear 36 being continuously driven through reducing gearing by a motor 38. The clutch mechanism employed may be similar to that disclosed in Letters Patent of the United States No. 1,674,085, granted June 19, 1928, on an application of Ballard and Seely, to which reference may be had for a further explanation of that part of the machine.

40 The shoe support comprises a plate 40 shaped like the forepart of the bottom of a shoe and large enough to support the forepart of the shoe bottom, including the outwardly projecting margin of the sole. The plate 40 is secured to a block 42 mounted upon the upper end of a shaft 46 which is arranged for longitudinal movement in an elongated bearing extending upwardly and rearwardly at a slight inclination to the vertical and formed in the frame 10 of the machine. The 45 shaft 46, together with the block 42 and shoe support 40, is arranged to be moved upwardly by power of the machine and for this purpose it is connected at its lower end to toggle links 52, 54. The upper toggle link 52 is pivotally connected to a sliding block 48 which is freely movable in a slot in the lower end of the shaft 46, being prevented from displacement by a strap 50 extending about the lower end of the shaft. The 50 toggle links 52, 54 are operated by a cam bar 56 which is forked to embrace a collar on the main shaft 12 and is provided with a cam roll 58 running in the cam track 16 formed in the clutch disk 14. The lower end of the toggle link 54 is supported by an adjustable abutment 60 which is upheld by a heavy spring, as more fully disclosed in Letters Patent of the United States No. 1,861,832, granted June 7, 1932, on application of W. C. Baxter. The initial heightwise position of the shoe support 40 is determined by 55 a stop screw 62 projecting downwardly from a bracket 64 which is formed as part of the block 42 on which the support 40 rests, the said screw 62 being arranged to engage the frame 10 when the work support is in its lowest position. The 60 lost motion provided for the block 48 in the lower

end of the shaft 46 permits initial heightwise adjustment for the support 40 by means of the screw 62 and also permits the adjustment of the abutment 60 to vary the initial pressure which will be exerted on the shoe parts when 5 the toggle 52, 54 is straightened. An abutment 66 for the rear end of the shoe is provided which may be initially set at a short distance from the rear end of the shoe to permit ready insertion of shoes of the size being operated upon and which, by depression of the treadle 32, is moved to engage the shoe and is held against the shoe at first by the treadle and later by power operation of the machine, the construction and operation of this portion of the machine being fully 15 disclosed in the Baxter Patent No. 1,955,730 referred to above.

The machine is provided with end-embracing means or wipers 70 which preferably, as disclosed in the last-mentioned patent, are vertically stationary and are arranged for advancing and closing movement. Two means for advancing and closing the wipers are provided, one means being the handwheel 72 by which the wipers may be advanced and closed to correspond to the 25 size and shape of the toe end of the last of the shoe being operated upon and the other means being a positively power-operated lever 76 by which a predetermined amount of advancing and closing movement may be imparted to the wipers. 30 The amount of such predetermined advancing and closing movement is determined by the setting of a screw 74 carried by the upper end of the lever 76. The lever 76 is pivoted to the machine frame at 78 and carries at its lower end 35 a roll 80 mounted on the pin 82 and engaging an edge cam 84 on the clutch disk 14, said edge cam having a rise or projection 86 which, upon engagement with the roll 80, operates the lever to advance and close the wipers 70. By the 40 organization above described, the advancing and closing movement of the wipers will occur after the outturned flange of the upper is pressed firmly against the projecting margin of the sole. While machines thus organized are satisfactory 45 for the general run of stitchdown work, it is found that some manufacturers employ lasts the sides of which recede inwardly in the region next to the last bottom, that is, the sides of the last are undercut. Under such conditions fastenings used preliminarily to fasten the upper to the sole in pulled-over condition are located under the overhang of the last and hence wipers 50 set to correspond to the largest outline of the last will, upon movement of the shoe support, engage the upper outside of the fastenings and, when the wipers are advanced and closed with the upper and sole under pressure between them and the shoe support, they will engage and shear off or otherwise injure the preliminary fastenings. The construction about to be described provides means for causing the wiper advancing and closing movement to occur earlier in the 55 cycle, that is, before the shoe support is fully raised, whereby the wipers are caused to close in under the overhang of the last and be located on top of the preliminary fastenings when their final advancing and closing movement occurs, thus avoiding injury to the preliminary fastenings and effecting a better lasting operation.

For this purpose there is pivoted upon the pin 60 82 which carries the roll 80 a lever 90 the lower end of which carries a roll 92 similar to the roll 80 and the upper arm of which carries a screw 94 arranged to engage a face on the lever 76 and 75

to provide means for adjusting the lever 90 about its fulcrum 82. It will be seen that by adjusting the screw 94 the roll 92 may be moved toward and away from the cam 84 and that when adjusted toward the cam but not into contact with it, the projection 86 of the cam 84 will first engage the roll 92, producing a partial advancing and closing movement of the wipers, and that later in the cycle the projection 86 will engage the roll 80 and complete the advancing and closing movement of the wipers.

In order that the operator may readily ascertain what position the roll 92 is made to assume by turning the screw 94, an indicator 95 is provided which cooperates with a scale 97 secured to a casing 99 hinged to the machine frame. The indicator 95 is formed on the outer end of a bar 101 having between its ends a slot engaging a pin 103 fixed in the lever 90. The inner end of the bar 101 is pivoted at 105 to the lever 76 at such a point that the bar 101 is in angular relation to the path of movement of the pin 103 due to movement of the lever 90 so that the bar will move about its pivot 100 as the screw 94 is operated to adjust the lever 90 relatively to the lever 76. As shown, when the roll 92 is adjusted away from the cam 84 far enough so that the projection 86 will not move it, the indicator 95 will be at the upper or zero end of the scale 97. Thus, by adjusting the screw 94 any portion of the advancing and closing movements of the wipers may be caused to occur earlier in the cycle, that is, before the work support 40 is completely raised, and the remainder of those movements will occur when the movement of the work support has been substantially completed. Since the distance from the fulcrum 78 of the lever 76 to the roll 80 is considerably less than the distance from the fulcrum 78 to the roll 92, it may appear that the advancing and closing movements imparted to the wipers by action of the projection 86 upon the roll 80 will be greater than the movements imparted to the wipers by the same projection acting solely upon the roll 92 when it is adjusted close to the cam to receive the entire effect of the projection 86 to the exclusion of the roll 80. As a matter of fact, however, with the construction disclosed substantially the same advancing and closing movement is imparted to the wipers whether the roll 80 is employed to the exclusion of the roll 92 or whether the roll 92 is employed to the exclusion of the roll 80. The reason for this will be readily seen by considering the relation of the path of the center of the roll 80 about its center 76 to a radius of the cam extended through the center of the roll 80 and the relation of the path of the roll 92 about its center 78 to a radius of the cam extended through the center of the roll 92. In the first instance it will be seen that the path of the cam roll 80 is nearly parallel to the radius passing through the center of the roll while the path of the cam roll 92 is at a very substantial angle to the radius passing through the center of the roll 92. Thus, the path through which the center of the cam roll 90 is moved by the projection 86 is enough longer than the path through which the center of the cam roll 80 moves when acted upon by the same projection to offset the greater distance of the cam roll 92 from the center 78 about which it moves, and the amount of advancing and closing movement of the wipers will be substantially the same whether the roll 80 or the roll 92 is employed.

solely to produce that movement. It is to be noted, however, that when the roll 92 is employed to the exclusion of the roll 80, a greater angular movement of the projection 86 is required to produce the entire advancing and closing movement of the wipers than when the roll 80 is employed to the exclusion of the roll 92.

In the illustrated machine the cam track 16 is so constructed that, while the projection 86 is acting either on the roll 92 or on the roll 80 to effect advancing and closing movements of the wipers, the roll 58 will be in a portion of the cam track 16 which is concentric with the shaft 12. Thus heightwise movement of the shoe support does not occur during such movements of the wipers. Stated more in detail, during the first 70 degrees of angular clockwise movement of the cam block 14 from the starting position shown, the cam track 16 moves the roll 58 to the right to operate the toggle 52, 54 to raise the work support to cause the upper to be shaped over the toe portion of the shoe. At this time the projection 86 is about to act on the roll 92 if that roll is adjusted into operative position. Then for about 30 degrees the cam path 16 is concentric with the shaft, causing the heightwise movement of the shoe support to cease while the projection 86 is acting to move the roll 92. Then for about 15 degrees while the projection 86 is approaching the roll 80 the cam track 16 continues to move the shoe support upwardly, pausing again for 30 degrees while the projection 86 is acting to move the roll 80. Then after the final closing of the wipers the cam 16 acts to complete the straightening of the toggle to apply the final pressure to the outturned flange of the upper and the projecting margin of the sole, the machine of course stopping at this point, after about 180 degrees of rotation of the cam 14, with the shoe under pressure.

The machine is preferably, though not necessarily, provided with a plurality of pairs of pincer jaws 96, a pair being located at each corner of the toe and at each side of the toe, the pincers being located below the wipers in position to engage the outspread margin of the upper when the shoe is introduced into the machine. The construction and operation of such pincers is fully disclosed in the Baxter Patent No. 1,955,730. The initial closing movement of the pincers is effected by depression of the treadle 32 which is connected by a rod 98 to a lever 100 fulcrumed on the lower portion of the shaft 46 at 102 and having a lost-motion connection to links 104 by a pin 106 to which the fulcrum may be shifted when the shaft 46 is operated by power. The rear end of the lever 100 is connected through springs 108 to the lower jaws of the pincers 96 so that when the treadle is depressed the pincers will be closed upon the work at the same time that the abutment 66 is brought into engagement with the shoe. As in the prior construction, it is desirable to withdraw the pincer jaws from between the wipers 70 and the work support 40 before they become pinched therebetween by the upward pressure of the work support. This is effected by a lever 110 pivoted at 78 and having on its lower arm a roll 112 engaging an edge cam 114 and mounted to rotate with the clutch disk 14. The upper arm of the lever 110 is connected by a link 116 to the mechanism by which the pincers are carried. The cam 114 operates to swing the lever 110 counterclockwise to effect bodily withdrawal of the corner pincers and rotation of the side pincers to carry them away from the shoe at 75

a time to avoid the pincers being caught between the wipers 70 and the work support 40. Since the construction and mounting of the pincers is clearly disclosed in the last-mentioned patent, 5 it is not necessary to present further details of the construction.

It is desirable, in conjunction with the treadle- 10 effected operation of the abutment 66 and the pincers 96 to apply pressure to the shoe upper in the vicinity of the tip line to hold it firmly clamped against the last during the lasting operation, that is, during the operation of the wiper 70 and the pincers 96, so as to prevent the combined action of the pincers and wipers or either 15 of them from so pulling the upper longitudinally that it will bridge between the toe and the throat of the vamp. Once this bridging has occurred it is ineffective to press the upper against the last and difficult to apply sufficient tension to draw it down to the wood again. In the illustrated construction, however, the upper is firmly clamped to the last prior to the operation of the pincers and wipers or either of them so that the upper has no opportunity to become bridged and hence after 20 the lasting operation the upper remains tightly against the last. A pad 120 is arranged to be moved vertically against the toe portion of the upper, the initial portion of the movement of the treadle 32 being utilized to effect this operation. 25 The pad 120 is mounted on the lower end of a stem 122 which extends upwardly through a member 124. Mounted on the stem 122 is a compression spring 126 the initial tension of which may be adjusted by moving a collar 128 up and 30 down on the stem, the spring being arranged yieldingly to oppose upward movement of the pad 120. Bodily vertical adjustment of the pad 120 relatively to the shoe without affecting the tension of the spring 126 may be effected by rotating 35 the head 130.

The member 124 is pivoted at 132 to an arm 134 to permit swinging movement of the pad 120 longitudinally of the shoe, and its position forwardly of the shoe is adjustably determined by a 40 screw 136 threaded through a projection on the member 124 and engaging a surface formed on the arm 134. The arm 134 is mounted for movement about a vertical axis on a vertically movable rack bar 138. A reduced portion of the bar 45 138 extends through a vertical bore in the arm 134 upon which it is held by a nut 140. Above the nut is a further reduced cylindrical portion 142 of the bar 138 which is guided in a suitable bearing formed in a bracket 144, secured to the 50 frame, in which the rack bar 138 is mounted. The rack bar 138 is normally maintained in an elevated position by a compression spring (not shown) located between the lower end of the bar 138 and the fixed part of the frame of the machine. The rack bar 138 is engaged by a pinion 146 fixed to a shaft 148 on which is an arm 150. The construction above described relating to the 55 toe pressing pad 120 and its mounting is substantially similar to that more fully described in an application for Letters Patent of the United States Serial No. 21,597 filed of even date here-with in the name of J. C. Cantley.

In the present construction the arm 150 carries a roll 152. A cam member 154 is pivoted 60 on a shaft 156 below the shaft 148 and is located between two threaded lugs 158, 160 formed on a lever 162 also pivoted on the shaft 156 and having a forward projection 164 carrying a stop screw to limit its clockwise movement. Adjusting screws threaded through the lug 158, 160

engage the cam member 154 and serve as means for adjusting the cam member relatively to the lever 162. Pivoted at 166 to the lever 162 is a bar or rod 168 having near its lower end a hook to engage a pin 170 carried by a lever 172. The lever 172 has slotted ears spaced to receive the bifurcated forward end of a lever 174 pivoted at 176 to the machine frame and connected by a rod 178 to the treadle 32. A pin 180 passes through the slotted ears on the lever 172, through the bifurcated end of the lever 174 and through the lower end of a link 182 the upper end of which is connected by a link 184 to the upper arm 186 of a lever pivoted at 188, the lower arm of which carries a screw 190 engaging the bar 168. Fully crumpled at 192 to a bracket 194 is a lever 196 which at its rear end is connected at 198 by a link 200 to the lever 162. The pivot 198 of the lever 196 is on a rearward extension of the bracket 194, and a torsion spring 202 tends to 20 turn the lever 196 in a clockwise direction, thus urging the bar 168 toward the pin 170. On the forward end of the lever 196 is a pin 204 which cooperates with a hook-like recess 206 in the link 182. The forward end of the link 184 is slotted 25 longitudinally and connected by a pin 208 to the upper end of the link 182, the pin being maintained at the rear end of the slot by a tension spring 210 connected between the pin 208 and the lever 196. The wiper lever 70 is provided with 30 a lug 212 through which is threaded a screw 214 in position to engage the bar 168 when the wipers are operated and to swing the bar forwardly to disengage it from the pin 170. As the bar 168 swings forwardly it presses on the screw 190 on 35 the lower arm of the lever 174 and swings the lever counterclockwise. The action of the mechanism may now best be explained by starting at the beginning with the depression of the treadle.

Depression of the treadle 32 acts through the 40 treadle rod 98 to bring the abutment 66 against the shoe and to operate the lever 196 to bring the pincers into operative position. This occurs during the motion of the pin 180 in the slotted ears of the lever 172 without moving the lever. Further depression of the treadle then swings the lever 172 to operate the toe presser 120, this motion occurring of course before the tripping of the clutch to start the machine. As the lever 172 is swung counterclockwise by the motion of 45 the treadle the pin 170 pulls downwardly on the bar 168, causing the lever 162 to turn counterclockwise about its pivot 166 and the cam member 154 to engage the roll 152 on the arm 150, thus moving the arm 150 in a clockwise direction to 50 operate the pinion 146 and depress the rack bar 138 to press the pad 120 upon the shoe, the spring 126 yielding to permit such movement of the rack bar. When the flat top face of the cam member 154 moves under the roll 152 the presser 55 120 becomes locked in operative position and a reverse movement of the lever 162 is required to release it. During the counterclockwise movement of the lever 172 the link 200 swings the lever 196 in a counterclockwise direction about its 60 pivot 198, causing its forward end carrying the pin 204 to assume the dotted line position shown in which the pin is opposite the upper portion of the link 182 which, during depression of the treadle, has moved downwardly, the recess 206 being then of course below the pin 204. When the operator releases the treadle, the link 182 will move upwardly, bringing the recess 206 above the pin 204 and, when the wipers are operated, the screw 214 will swing the bar 168 forwardly, 65 70 75 75

engaging the screw 190 and swinging the lever 186 in a counterclockwise direction, causing the link 184 to swing the link 182 rearwardly and bring the recess 206 over the pin 204, the machine stopping with the parts in this position.

When the treadle is depressed the second time to cause it to complete its cycle and release the shoe, the link 182 will pull downwardly on the pin 204, turning the lever 196 in a clockwise direction, thereby pushing upwardly on the link 200 and effecting clockwise movement of the lever 162 to release the cam 154 from the roll 152, thus allowing the rack bar 138 to rise and lift the pad 120 away from the shoe.

Should the operator fail to release the treadle prior to the action of the wipers in the first half cycle of the machine, the movement of the lever 186 effected by the wiper lever 76 would merely pull the link 182 against the pin 204, the spring 210 then being stretched to permit completion of the movement of the lever 186. Upon release of the treadle after the machine stops, the link 182 will move upwardly and the recess 206 will be swung into position over the pin 204 by the tension of the spring 210 ready for operation as described upon the second depression of the treadle.

The rear end abutment 66 is carried by a support 216 for the rear end of the shoe which is adjustable heightwise for heels of different heights by means of a screw 218 threaded through the bracket 64 and engaging a member 220 upon which the support 216 is mounted. The member 220 is pivoted on a pin 222 which is secured in a rocker member 224, and secured to the pin is a pointer 226 which cooperates with a graduated scale 228 secured to the member 220. Thus, the operator is able accurately to determine the proper adjustment of the support 216 heightwise of the shoe effected by the screw 218.

Having thus described my invention, what I claim as new and desire to secure by Letters Patent of the United States is:

1. In a machine for lasting the toe portion of a stitchdown shoe, the combination of end-embracing wipers, a shoe support to receive the shoe and last and to support the sole including its projecting marginal portion, power-operated means for effecting relative movement of the end-embracing means and the shoe support heightwise of the shoe to shape the upper about the last and to press its marginal portion against the projecting margin of the sole, said means being constructed and arranged to stop with the marginal portions of the shoe under pressure, a treadle for controlling said power-operated means, means for pressing the upper against the forepart of the last whereby movement of the upper relatively to the last is prevented during the action of the pincers, and means operated by a second depression of the treadle for releasing the pressure on the forepart of the last and subsequently releasing the pressure upon the marginal portion of the shoe and sole.

2. In a machine for shaping the end portion of a stitchdown shoe to its last, the combination of end-embracing wipers, a shoe support to receive the shoe and last and to support the shoe sole including its projecting marginal portion, power-operated means for effecting relative movement of the end-embracing wipers and the shoe support heightwise of the shoe to shape the upper about the last and to press its marginal portion against the projecting margin of the sole, manually operated means for controlling said power-operated means and causing it to stop with the shoe under pressure, means operated by said manually oper-

ated means for pressing the shoe upper against the last in the vicinity of the tip line before the relative heightwise movement between the wipers and the shoe support begins, and means operated by said manually operated means for releasing the pressure on the shoe upper and subsequently causing operation of said power-operated means to cause reverse relative movement between the wipers and the shoe support to release the shoe.

3. In a machine for lasting the toe portion of a stitchdown shoe, the combination of end-embracing wipers, a shoe support to receive the shoe and last and to support the sole including its projecting marginal portion, power-operated means for effecting movement of the shoe support heightwise of the shoe to shape the upper about the last and to press its marginal portion against the projecting margin of the sole, said means being constructed and arranged to stop with the marginal portions of the shoe under pressure, a treadle for controlling said power-operated means, means operated by the treadle for pressing the upper against the forepart of the last to prevent bridging of the upper between the toe and the throat of the vamp of the upper, said treadle acting later to cause operation of said power-operated means, and means operated by a second depression of the treadle for releasing the pressure on the forepart of the last and subsequently causing the power-operated means to move the shoe support reversely.

4. In a machine for lasting the toe portion of a stitchdown shoe, the combination of a shoe support constructed and arranged to receive the bottom of a shoe presented right side up and to support the sole of the shoe including the projecting margin of the sole, pincers located in position to engage the margin of the upper, power-operated means for closing the pincers and for relatively operating the pincers and the shoe support to tension the upper, a treadle depressible to initiate said power operation, means operated by the treadle for pressing the upper against the forepart of the last whereby movement of the upper relatively to the last is prevented during the action of the pincers, and means operated by a second depression of the treadle for releasing the pressure on the forepart.

5. In a machine for lasting the toe portion of a stitchdown shoe, the combination of end-embracing wipers constructed and arranged for advancing and closing movements, a shoe support constructed and arranged to receive the bottom of a shoe presented right side up to the wipers and to support the sole of the shoe including the projecting margin of the sole, pincers located beneath the wipers in position to engage the margin of the upper, power-operated means for closing the pincers and for relatively operating the wipers and the shoe support to tension the upper, a treadle depressible to initiate said power operation, means operated by the treadle for pressing the upper against the forepart of the last whereby movement of the upper relatively to the last is prevented during the action of the pincers and wipers in lasting the upper, means for advancing and closing the wipers substantially at the termination of the upward movement of the support, and means operated by a second depression of the treadle for releasing the pressure on the forepart and for thereafter causing the power-operated means relatively to move the wipers and shoe support to release the shoe.

6. In a lasting machine, the combination of

end-embracing wipers, a wiper lever, a power-operated cam for operating the wiper lever at a predetermined time in the cycle of the machine, an extension on the wiper lever, and means for 5 locating the extension in position to engage the cam to cause action of the cam upon the wiper lever to occur at a different time in the cycle of the machine.

7. In a lasting machine, the combination of 10 end-embracing wipers, a wiper lever, a power-operated cam for operating the wiper lever at a predetermined time in the cycle of the machine, an extension on the wiper lever, and means for 15 locating the extension in engagement with the cam to cause action of the cam upon the wiper lever to occur earlier in the cycle of the machine.

8. In a lasting machine, the combination of 20 end-embracing wipers, a wiper lever, a power-operated cam for operating the wiper lever at a predetermined time in the cycle of the machine, an extension on the wiper lever normally inoperative by the cam, and means for adjusting the 25 extension toward the cam to cause part of the action of the cam upon the wiper lever to occur prior to said predetermined time.

9. In a machine for shaping the end portion of 30 a stitchdown shoe to its last, the combination of end-embracing wipers, a shoe support to receive the shoe and last, means for effecting relative movement between the end-embracing wipers and the shoe support heightwise of the shoe to 35 shape the upper about the last, means for effecting operation of the wipers substantially at the termination of said relative heightwise movement, and means operable at will for causing operation of the wipers prior to the completion of said relative heightwise movement.

10. In a machine for shaping the end portion of 40 a stitchdown shoe to its last, the combination of end-embracing wipers, a shoe support to receive the shoe and last, means for effecting relative movement between the end-embracing wipers and the shoe support heightwise of the shoe to 45 shape the upper about the last, means for effecting advancing movement of the wipers substantially at the termination of said relative heightwise movement, and means operable at will for causing part of the movement of the wipers to occur prior to the completion of said relative 50 heightwise movement.

11. In a machine for shaping the end portion of 55 a stitchdown shoe to its last, the combination of end-embracing wipers, a shoe support to receive the shoe and last, means for effecting relative movement between the end-embracing wipers and the shoe support heightwise of the shoe to 60 shape the upper about the last, means for effecting operative movement of the wipers substantially at the termination of said relative heightwise movement, and means operable at will for causing part of the movement of the wipers to occur prior to the completion of said relative 65 heightwise movement, the remainder of the operative movement occurring at the termination of said relative heightwise movement.

12. In a machine for shaping the end portion of 70 a stitchdown shoe to its last, the combination of end-embracing wipers arranged for advancing and closing movements, a shoe support to receive the shoe and last and to support the shoe sole including its projecting marginal portion, power-operated means for effecting relative movement 75 heightwise of the shoe between the wipers and the shoe support to shape the upper to the last and to press its marginal portion against the

projecting margin of the sole, power-operated means for advancing and closing the wipers substantially at the termination of said relative heightwise movement, and means arranged to be rendered operative at the will of the operator 5 for causing part or all of said advancing and closing movement of the wipers to occur earlier in the cycle and prior to the termination of said relative heightwise movement.

13. In a machine for shaping the end portion 10 of a stitchdown shoe to its last, the combination of end-embracing wipers arranged for advancing and closing movements, a shoe support to receive the shoe and last and to support the shoe sole including its projecting marginal portion, power-operated means for effecting relative movement heightwise of the shoe between the wipers and the shoe support to shape the upper to the last and to press its marginal portion against the projecting margin of the sole, power-operated means including a cam and lever for advancing and closing the wipers substantially at the termination of said relative heightwise movement, and an extension on said lever arranged to be rendered operative by said cam 25 at the will of the operator for causing part or all of said advancing and closing movement of the wipers to occur earlier in the cycle and prior to the termination of said relative heightwise movement. 29

14. In a machine for shaping the end portion 35 of a stitchdown shoe to its last, the combination of end-embracing wipers arranged for advancing and closing movements, a shoe support to receive the shoe and last and to support the shoe sole 40 including its projecting marginal portion, power-operated means for effecting relative movement heightwise of the shoe between the wipers and the shoe support to shape the upper to the last and to press its marginal portion against the projecting margin of the sole, power-operated cam means for advancing and closing the wipers substantially at the termination of said relative heightwise movement, and means arranged to be 45 adjusted into position to be operated by said cam means for causing part of said advancing and closing movements of the wipers to occur earlier in the cycle and prior to the termination of said relative heightwise movement, said cam acting later in the cycle to complete the wiper movements. 50

15. In a machine for shaping the end portion 55 of a stitchdown shoe to its last, the combination of end-embracing wipers arranged for advancing and closing movements, a shoe support to receive the shoe and last and to support the shoe sole including its projecting marginal portion, power-operated means for effecting relative movement heightwise of the shoe between the wipers and the shoe support to shape the upper to 60 the last, means for advancing and closing the wipers prior to the completion of said relative heightwise movement to conform the upper to lasts the sides of which overhang the last bottom, and means for completing said advancing 65 and closing movements substantially at the termination of said relative heightwise movement to tuck the upper under the last bottom.

16. In a machine for shaping the end portion 70 of a stitchdown shoe to its last, the combination of end-embracing wipers arranged for advancing and closing movements, a shoe support to receive the shoe and last and to support the shoe sole including its projecting marginal portion, power-operated means for effecting relative movement 75

heightwise of the shoe between the wipers and the shoe support to shape the upper to the last and press its marginal portion against the projecting margin of the sole, power-operated cam 5 means for advancing and closing the wipers substantially at the termination of said relative heightwise movement, and means arranged to be adjusted into position to be operated by said cam means for causing a part of said advancing and 10 closing movement of the wipers to occur prior to the termination of said relative heightwise movement to cause the wipers to conform the upper to the side of the last which is undercut, said cam acting later in the cycle to complete the 15 wiper movements substantially at the termination of said relative heightwise movement to tuck the upper under the last bottom.

17. In a machine for shaping the end portion of a stitchdown shoe to its last, the combination 20 of end-embracing wipers arranged for advancing and closing movements, a shoe support to receive the shoe and last and to support the shoe sole including its projecting marginal portion, power-operated means for effecting relative 25 movement heightwise of the shoe between the wipers and the shoe support to shape the upper to the last, said means being constructed and arranged to effect said movement in a succession of steps with pauses between said steps, means 30 for advancing and closing the wipers prior to the completion of said relative heightwise movement during one of said pauses to conform the upper to lasts the sides of which overhang the last bottom, and means for completing said advancing and closing movements during another pause 35 substantially at the termination of said relative heightwise movement to tuck the upper under the last bottom.

18. In a machine for shaping the end portion 40 of a stitchdown shoe to its last, the combination of end-embracing wipers arranged for advancing and closing movements, a shoe support to receive the shoe and last and to support the shoe sole including its projecting marginal portion, power-operated means for effecting relative movement 45 heightwise of the shoe between the wipers and the shoe support to shape the upper to the last and

press its marginal portion against the projecting margin of the sole, power-operated cam means for advancing and closing the wipers substantially at the termination of said relative heightwise movement, and means arranged to be adjusted into 5 position to be operated by said cam means for causing a part of said advancing and closing movement of the wipers to occur prior to the termination of said relative heightwise movement to cause the wipers to conform the upper 10 to the side of the last which is undercut, said cam acting later in the cycle to complete the wiper movements substantially at the termination of said relative heightwise movement and said cam having concentric portions to cause relative 15 heightwise movement between the wipers and the shoe support to cease while the wipers are being operated.

19. In a machine for shaping the end portion 20 of a stitchdown shoe to its last, the combination of end-embracing wipers arranged for advancing and closing movements, a shoe support to receive the shoe and last and to support the shoe sole including its projecting marginal portion, power-operated means for effecting relative movement 25 heightwise of the shoe between the wipers and the shoe support to shape the upper to the last and press its marginal portion against the projecting margin of the sole, power-operated cam means for advancing and closing the wipers substantially 30 at the termination of said relative heightwise movement, a roll movable into position to be operated by said cam means for causing a part of said advancing and closing movement of the wipers to occur prior to the termination 35 of said relative heightwise movement to cause the wipers to conform the upper to the side of the last which is undercut, means for moving the roll into position to be operated by said cam, and an indicator movable in proportion to said adjustment to indicate the operative position of the roll with respect to the cam, said cam acting later in the cycle to complete the wiper movements substantially at the termination of said relative heightwise movement. 40 45

FRANCIS J. BETTER.
